METAL CURTAIN

Charles S. White, Dearborn, Mich., assignor by
mesne assignments, of one-half to A. E. Wilson
and one-half to Harry J. Heiden, both of De-
troit, Mich.

Application July 26, 1947, Serial No. 763,797

3 Claims. (Cl. 160—133)

1

This invention relates to an improved metal curtain or awning.

The principal objects of this invention are to provide an improved metal curtain or awning made of a plurality of like sheet metal elements adapted, when extended, to be disposed in a substantially flat plane and adapted to be rolled into a relatively small diameter cylinder for storage purposes or when not in use; to provide a metal curtain or awning of the aforementioned type which is extremely light in weight, inexpensive to manufacture, and long lasting; to provide a metal curtain or awning of the aforementioned type which may be used as an angularly extending curtain or awning for a window or as a drop curtain or awning for a window, porch, or the like; to provide a metal curtain or awning of the aforementioned type which may be inexpensively finished in any desired manner or color so as to be attractive in appearance and fit into any desired color scheme; to provide a metal curtain or awning of the aforementioned type which will not kink or lose its shape, and which is provided with improved means for retaining the like sheet metal elements in a substantially flat plane when the awning or curtain is in an extended position, and for permitting the elements to be compactly rolled upon a relatively small roller into a storage container or easing, without distorting or injuring the elements.

These and other objects of this invention will become apparent from the following detailed description taken in conjunction with the accompanying drawing in which:

Figure 1 is a perspective view of the curtain of this invention extended over a window;

Fig. 2 is an enlarged transverse sectional view of the curtain of this invention in a rolled up position; and

Fig. 3 is an enlarged fragmentary perspective view of a portion of the structure illustrated in Fig. 1.

Referring now to the drawing, it will be seen that the metal curtain, generally indicated at 5, comprises a plurality of longitudinally extending like sheet metal elements 7 which are hingedly interconnected, as will be hereinafter described, to form the completed curtain. The curtain elements 7 may be made of aluminum and painted, but preferably are made of stainless steel of a very light gauge and furnished in an unpainted condition. The surface of the elements may be polished, may be left in a natural condition, or a matte finish may be provided thereon. In this way the surface of the curtain may be finished

in any desired manner to conform to the color scheme or type of finish that a user desires.

The interconnecting hinge arrangement of the elements 7 permits the curtain to be wound into a cylindrical shape on a roller 9, which is illustrated in Fig. 1 as mounted on brackets 11 which in turn are secured on the wall of the building over a window 13. When the curtain illustrated in Fig. 1 is unwound and extended it is supported on a conventional awning or curtain support 12 which is secured to the wall of the building. However, it is to be understood that the metal curtain 5 may be used as an awning or a curtain for any type of window and disposed in any angular relation with respect to the latter, or it may be used as a drop to be employed in conjunction with, for example, a porch screen or a suitable window structure.

While the size of the roller 9 and the dimensions of the elements 7 may be in any predetermined relationship, for purposes of illustration the curtain herein shown is adapted to be wound on a roller 9 of a 2" diameter, and the dimensions referred to, for the elements 7, are only to be construed as preferred dimensions for the elements in order to roll them around the 2" roller.

The center portion 15 of each element 7 is arcuate in transverse section and struck on a large radius having its point of center 17 on one side 30 of the vertical center line thereof. The arcuate shape of each element 7 provides strength along the longitudinal dimension thereof against bending so that the elements will not kink or lose their shape over long periods of use. One end of each of the elements 7 is arched downwardly at 19 on a shorter radius than the center portion 15, and the point of center 21 of this radius is illustrated as being above and in vertical alignment with the center point 17. The lower end of the arched portion 19 of each element 7 is extended flat to form a web 23 which extends downwardly from the arched end portion 19 on an angle of substantially 45° with respect to the horizontal. The lower end of the web portion 23 is reversely coiled at 25 into a partial cylinder to provide a female hinge portion along one transverse edge of each element 7.

The opposite end of each element 7 is curved downwardly at 27 and extended flat to form a web 29 which extends parallel to the web 23 on the opposite end of each element. The lower end of the web 29 is reversely coiled at 31 into a partial cylinder, of smaller diameter than the opposite partial cylinder 25 to provide a male hinge portion along the opposite transverse edge of each

element 7 which is in horizontal alignment with the cylindrical female hinge portion 25.

As the elements 7 are identical in construction they may be assembled by telescoping the male hinge portion 31 of each element into the female hinge portion 25 of the adjacent element, so that a plurality of the longitudinally extending elements from the curtain 5. It will be noted that when the elements are hingedly interconnected the upper surface of the arched end portion 19 of each element 7 is higher in elevation than the opposite curved end portion 27 so that the top surfaces of the elements lie in a substantially flat plane, and therefore provide a curtain which is more attractive in appearance and efficient in operation. When the curtain is in its extended position, so as to lie on the curtain support 12, the web 29, adjacent the male hinge portion 31 of each element, abuts the parallel web portion 23, adjacent the interconnected female hinge portion 25 of each element, so that the elements will be positively retained in a substantially flat plane. In this way relative upward movement between the elements is prevented by the abutting webs, and relative downward movement is prevented by the curtain support 12. While the abutting webs of each element act as stops when the curtain is extended, the elements 7 can be rolled into a cylindrical shape about the roller 9, as indicated in Fig. 2.

As best seen in Fig. 2 the innermost element 7, adjacent the roller 9, has its female hinge portion 25 cut off, so that the arcuate center portion 15 thereof is secured to the roller 9 by means of a rivet 33. The male hinge portion 31 is then telescoped into the female hinge portion 25 on the adjacent element 7 and the remainder of the elements are interconnected as described above. When the roller 9 is rotated the interengaging male and female hinge portions of the elements will pivot with respect to each other to permit 90° hinged movement of the elements so that they may be wound around the roller 9 without any deformation or damage thereto. The pivotal movement between the elements is limited to 90° as the end of the coil of one element will abut against the web portion of its adjacent element. The elements, due to the correlation between their dimension and the dimension of the roller, will thus wind around the roller and each other without causing any deformation thereof.

In the embodiment illustrated in the drawing 10 feet of curtain may be rolled into a 6 3/4" cylinder about the roller 9 and can therefore if desired be disposed within a 7" or 8" container 35, shown in dot and dash in Fig. 2. The curtain thus may be substituted for a canvas awning or may be employed as a drop for a porch or a window, and due to its metal construction will outlast canvas or any other type of fabric, many times over.

I claim:

1. In a curtain, a plurality of longitudinally extending elements in hinged relation to each other, the body of each of said elements having its transverse section formed on an arc of large radius, one edge of said element being struck on an arc of smaller radius and then extended at an angle to the transverse section to form a flat web

and then coiled into a partial cylinder, the opposite edge of said element being curved downwardly and extended at the same angle from the transverse plane of the element to form a web at the opposite end thereof and then coiled into a cylinder of smaller diameter such that it may be telescoped into said first cylinder so as to have the elements capable of being assembled by the interengagement of said telescoping cylinders and prevented from moving beyond the plane of the top surfaces of the adjacent elements by the engagement of said webs.

2. A longitudinally extending element, a plurality of which form a curtain, having an arcuate transverse section struck on a large radius having its point of center on one side of the center line of the element to provide strength along the longitudinal dimension thereof against bending, one edge of said element being arched downwardly on a shorter radius also spaced from the center line of the element and then extended flat to form a web and reversely coiled into a female hinge portion, the opposite edge of said element being curved downwardly and extended flat to form a web and reversely coiled into a male hinge portion capable of telescoping into the female hinge portion of a like element, whereby a plurality of said elements may be secured together and wound on a roller without distortion.

3. In a curtain, a plurality of longitudinally extending elements, each of said elements having an arcuate transverse section struck on a large radius having its point of center on one side of the center line of the element to provide strength along the longitudinal dimension against bending, one edge of said element being curved downwardly and extended flat to form a web and reversely coiled into a male hinge portion, the opposite edge of said element being arched downwardly on a shorter radius than the arcuate transverse section and having its point of center on one side of the center line of the element and then extended flat to form a web and reversely coiled into a female hinge portion, the upper surfaces of the said arched end being higher in elevation than the opposite curved edge portion so that when the male hinge portions are telescoped into the adjacent female hinge portions the elements will be disposed in a substantially flat plane, said hinged portions and webs being arranged and spaced so as to permit said hinges to pivot 90° and permit said plurality of elements to be wound on a roller without distortion.
